UNITED STATES PATENT OFFICE.

ARCHIE H. CRAMPTON, OF CHICAGO, ILLINOIS.

LATCH.

1,211,549.

Specification of Letters Patent.

Patented Jan. 9, 1917.

Application filed September 4, 1915. Serial No. 49,023.

To all whom it may concern:

Be it known that I, ARCHIE H. CRAMPTON, a citizen of the United States, residing at Chicago, in the county of Cook and State 5 of Illinois, have invented certain new and useful Improvements in Latches, of which the following is a specification.

This invention relates to improvements in latches and more particularly to pressure 10 latches and its object is to produce a latch of this class for general use although peculiarly for use on refrigerators and similar containers.

Another object is to produce a latch of 15 this class that is very simple in construction, cheap to manufacture, that is simplicity itself in operation and that, withal, possesses the maximum efficiency.

The latch comprises a keeper having a 20 resilient pocket which serves as a shock absorber as it receives the locking bolt thus effectually arresting all pounding or jolting incident to slamming the door; the keeper and bolt tend slightly to throw the door outward or into open position thus relieving 25 the door hinges of some of the strain incident to the weight of the door and keeping the door "primed" for instantaneous opening.

30 A further object of the device is to produce a latch provided with a one-piece metal operating handle fulcrumed upon a center-of-motion pin within the latch casing, said handle having, crimped or stamped thereon, 35 a one piece metal sleeve.

With the foregoing and other objects in view the invention consists in the combination and arrangement of parts to be herein-after fully described in the following specification, pointed out in the appended claims and clearly illustrated in the accompanying drawings which form a part of said specification and in which—

Figure 1 is a side elevation of my improved latch showing its application, the latch and door being shown in open position in full lines, and in closed position in dotted lines. Fig. 2 is a plan view. Fig. 3 is a vertical sectional view, closed position. Fig. 4 is a similar view in open position, the dotted lines showing the normal position of the handle after the latch has been opened. Fig. 5 is an inverted plan view of the latch.

Like reference characters indicate corresponding parts throughout the several views.

The reference numeral 1 denotes a door and 2 the door jamb.

My improved latch comprises the outer flanged casing 3 adapted to be suitably secured to the door 1, the casing being formed 60 with an opening 4 in one end. Within the casing 3 a casing 6 is disposed which is formed with openings in alinement with the openings specified in the outer casing, said inner casing being formed essentially with 65 lateral ears 7, 8 the former being perforated in alinement with similar perforations in the outer casing to receive the pin 9, and the latter ears being formed with elongated openings 10 to permit the device to be assembled and to permit insertion 70 of the bolt 11, said opening 10 being somewhat larger than alined perforations in the outer casing; the ears 7, 8 and the ends of the casing 6 resting against the 75 door. The inner casing, further, is formed with a longitudinal opening 12 in one end, and an inwardly extending finger 14 serves as a stop finger in a manner to be herein-after brought out.

The handle 15 is fulcrumed upon the pin 9 and extends through the alined openings in the ends of the outer and inner casings and is formed with an angular inner termination 16 which is adapted for engagement 85 with a link 17 also fulcrumed upon the pin 9 and about said link a coil spring 18 is disposed which at one end abuts said pin 9 and which abuts a shoe 19 at its other end, which shoe is slidably arranged upon said link and 90 is formed with an angular termination adapted for engagement with the door 1 when the latch is closed. A yoke 20, the ends of which extend through the bolt 11, passes through the link 17 and is in frictional engagement with the face of the shoe 19 whereby it is yieldingly retained against the adjacent end of said link, one of the ends of said yoke being disposed in the plane of and capable of engagement with the stop 100 14 when the latch is open whereby the movement of said yoke is limited.

The keeper which is adapted to receive the beveled free end of the bolt 11 is formed of a single piece of resilient material 21, the 105 ends of which are secured to the door jamb and between said ends an approximately U-shaped pocket 22 is formed the base of which is yieldingly retained a short distance away from the face of the jamb 2.

In Fig. 3 and in dotted lines Fig. 1 the latch is shown closed. To open it the handle 15 is raised to the position shown, full lines, Fig. 4 thus causing the end 16 thereof to

depress the link 17 and to move the yoke 20 longitudinally of said link thus moving the shoe 19 longitudinally of said link and compressing the spring 18 and at the same time 5 rotating the bolt 11 and causing the free end thereof to travel over one side of the pocket and into position shown, full lines, Fig. 2. As the link 17 moves toward the door it carries the shoe with it and the same encounters the surface of the door just previous to contact of one of the ends of the yoke with the stop 14, the shoe and its connection serving as a shock absorber. The handle will now gravitate into the position shown dotted, Fig. 4. To close the latch the door may be slammed and the bolt through contact with the keeper will be turned thus raising the yoke and link and the spring will force these members together with the shoe into 15 20 normal position.

What is claimed is:—

1. In a latch, an outer casing, an inner casing, a bolt extending through and beyond said casings, a pin connecting said casings, 25 a handle extending into said casings and fulcrumed on said pin, a link fulcrumed on said pin for engagement with one end of said handle, a member slidably arranged upon said link, a flexible member encircling said link and abutting said pin and sliding member for yieldingly keeping them the maximum distance apart, a yoke extending through said link in frictional engagement with said sliding member and terminally 30 35 embedded in the said bolt and a keeper for said bolt.
2. In a latch, an outer casing, an inner casing, a bolt extending through and beyond said casings, a pin connecting said casings, 40 a handle extending into said casings and fulcrumed on said pin, a link fulcrumed on said pin for engagement with one end of said handle, a member slidably arranged upon said link, a flexible member encircling said link and abutting said pin and sliding member for yieldingly keeping them the maximum distance apart, a yoke extending 45 through said link and in frictional engagement with said sliding member and terminally embedded in the said bolt, and a keeper formed with a resilient pocket to receive said bolt.
3. In a latch, an outer casing, an inner casing, a bolt extending through and beyond said casings, a pin connecting said casings, 50 a handle extending into said casings and fulcrumed on said pin, a link fulcrumed on said pin for engagement with one end of said handle, a member slidably arranged upon said link, a flexible member encircling said link and abutting said pin and sliding member for yieldingly keeping them the maximum distance apart, a yoke extending 55 through said link and in frictional engagement with said sliding member and terminally embedded in the said bolt, and a keeper formed with a resilient pocket to receive said bolt.
- 60

maximum distance apart, a yoke extending through said link and in frictional engagement with said sliding member and terminally embedded in said bolt, a finger formed integral with said inner casing for limiting the movement of said yoke and a keeper formed with a resilient pocket to receive said bolt.

65

4. In a latch, a perforated outer casing, an inner casing formed with inwardly extending lugs perforated in alinement with the perforations in said outer casing, a bolt extending through alined perforations in 70 said casings, a pin extending through alined perforations in said casings, a handle extending into said casings and fulcrumed on said pin, a link fulcrumed on said pin for engagement with one end of said handle, a 75 shoe slidably arranged on said link, a spring encircling said link and abutting said shoe and pin, a yoke extending through said link and in frictional engagement with said shoe and terminally embedded in said bolt, a finger formed integral with said inner casing for limiting the movement of said yoke and a keeper formed with a resilient pocket to receive said bolt.

70

5. In a latch, an outer casing, an inner 90 casing, a bolt for said casings, a pin connecting said casings, a link fulcrumed on said pin, a spring-pressed shoe slidably carried by said link, a finger formed integral with said inner casing, a yoke carried by said 95 bolt, and extending through said link and in frictional engagement with said shoe, the movement of said yoke being limited by said finger, manually operable means fulcrumed on said pin for engagement with said link 100 to actuate the same and its connections thereby actuating said bolt, and a keeper formed with a resilient pocket to receive said bolt.

95

6. In a door latch, an outer casing, an inner casing, a bolt for said casings, a pin connecting said casings, a yoke carried by said bolt, resilient shock-absorbing means fulcrumed on said pin and operatively engaging said yoke whereby the same and said bolt are yieldingly retained in adjusted relation, manually operable means fulcrumed on said pin for moving said resilient shock-absorbing means and connections from closed to open position and a keeper formed 105 with a resilient pocket to receive said bolt.

105

In testimony that I claim the foregoing as my own I have hereto affixed my signature in the presence of two subscribing witnesses.

ARCHIE H. CRAMPTON.
